UNITED STATES PATENT OFFICE.

DANIEL J. McISAAC, OF NEW YORK, N. Y.

DESIGN FOR A SHAVING-MIRROR AND SUPPORT.

44,537.

Specification for Design.

Patented Aug. 19, 1913.

Application filed December 11, 1912. Serial No. 736,210. Term of patent 3½ years.

To all whom it may concern:

Be it known that I, DANIEL J. McISAAC, a citizen of the United States, and resident of New York, in the county of New York and State of New York, have invented a certain new, original, and ornamental Design for Shaving-Mirrors and Supports, of which the following is a specification, reference being had to the accompanying drawing, forming a part thereof.

The figure is a front elevation of a shaving mirror and support showing my new design.

I claim:

The ornamental design for a shaving mirror and support, as shown.

Signed at New York in the county of New York and State of New York this nineteenth day of November A. D. 1912.

DANIEL J. McISAAC.
